SELECTOR SWITCH METERING CIRCUIT

Clarence E. Lomax, Chicago, Ill., assignor to Automatic Electric Laboratories, Inc., Chicago, Ill., a corporation of Delaware

Application January 2, 1947, Serial No. 719,650

4 Claims. (Cl. 179—8.5)

1

This invention relates in general to automatic switches in automatic telephone systems and more particularly to a novel circuit arrangement for metering overflow calls.

The object of the invention is to provide a novel system for metering overflow calls in an efficient and accurate manner and to provide exacting level or group level overflow supervision.

A feature of the invention is the manner in which a vertical bank and an associated vertical wiper are arranged to operate an overflow meter.

A further feature is the manner in which a plurality of meters may be connected in various arrangements to the vertical bank and thereby provide supervision for any level or group of levels of the associated switches.

Another feature is the manner in which a cam relay is arranged to prepare the operating circuit and the line relay and release relay are operated to complete the operating circuit over the vertical bank to the overflow meters.

The invention, both as to its organization and method of operation together with further objects and advantages thereof, will best be understood by reference to the following specification and the accompanying drawing.

Referring now to the drawing, the automatic switch there illustrated incorporates the features of the applicant's invention. The selector comprises incoming conductors 131, 132 and 133 and is controlled to operate by impulses received over these conductors to position wipers 134, 135 and 136 in a well-known manner opposite a desired group of bank contacts. The switch also includes an auxiliary contact bank 151 and a vertical wiper 150 of the type disclosed in British Patent 517,702 issued February 6, 1940 in which the vertical wiper moves vertically with the carriage shaft, and is free to rotate thereon and thereby remain engaged with its bank while the switch effects rotary movement of wipers 134, 135, and 136. A portion of a succeeding selector switch similar to the one shown in detail has been shown in block form as connected to one of the contacts of the switch bank accessible by wipers 134, 135 and 136. The contacts of the auxiliary bank are individually connected to jacks which are in turn convenient to a plurality of meters.

The selector is of the battery searching type and consists essentially of a well-known Strowger vertical and rotary switch having off normal springs 137 and cam springs 138 used in conjunction with a circuit including testing relay 10, switch through relay 20, electro polarized line

2

relay 30, release relay 40, series relay 50, cam slave relay 60, off normal relay 70, changeover relay 80, vertical magnet 90, release magnet 100, and rotary magnet 110, their associated contacts and conductors.

It will now be assumed that the selector is seized over the incoming conductors 131 to 133. A loop circuit is thereby closed for line relay 30 and series relay 50. Ground is connected to relay 80 over contacts 74 and conductor 133. Relay 80 operates and at its contacts 81 prepares a holding circuit for itself and an operating circuit for vertical magnet 90, at its contacts 82 opens a point in the operating circuit for release magnet 100, and at its contacts 83 opens a point in the operating circuit to rotary magnet 110. Relay 30 operates and at its contacts 31 completes an operating circuit over contacts 27 to relay 40. Relay 50 operates at the same time and at its contacts 51 completes a holding circuit to relay 40. Relay 40 operates and at its contacts 41 completes an auxiliary holding circuit for relay 80 over contacts 74, at its contacts 42 completes an operating circuit to cam relay 60 over normally closed cam springs 138, and at its contacts 43 prepares a point in the operating circuit to vertical magnet 90. Relay 60 operates and at its contacts 62 connects dial tone to conductor 131, at its contacts 63 completes an energizing circuit for the third winding of relay 30 over contacts 63 and 73, at its contacts 64 prepares a point in the circuit to the vertical magnet 90 and changeover magnet 80, at its contacts 66 prepares an operating circuit for testing relay 10, at its contacts 67 prepares a point in the operating circuit for switch through relay 20. The selector is now prepared for receipt of a series of impulses over the incoming conductors, relays 30, 40, 50, 60, and 80 being in an energized condition.

On receipt of the first break of the first impulse, line relays 30 and 50 de-energize. Line relay 30 at its contacts 31 opens the operating circuit to relay 40, and at its contacts 32 completes an operating circuit to vertical magnet 90 over contacts 27, 32, 43, 64, and 81. Vertical magnet 90 operates and elevates the wipers 134 to 136 one step whereby they are positioned in a well-known manner opposite the first level of bank contacts in the associated contact field. The wiper 150 is likewise positioned on the first contact of the auxiliary contact bank 151 which is common to the contact field in said first level. Incident to this first vertical step, the vertical off normal springs 137 are closed and an operat-

55

ing circuit is completed over same to relay 70. Relay 70 operates and at its contacts 72 removes dial tone from the line, at its contacts 73 inserts resistance 148 in series with the operating circuit for the third winding of polarized relay 30, at its contacts 75 completes a holding circuit to relay 80 over contacts 27, 32, 43, 64, 81 and 75, at its contacts 76 prepares a point in the operating circuit to release magnet 100, and at its contacts 77 prepares a point in the operating circuit to rotary magnet 110.

The vertical magnet elevates the wipers a number of levels relative to the number of impulses received. Relays 40 and 90 are slow to release and remain operated during the series of incoming impulses.

A short period after the cessation of the impulses of the first digit, relay 80 releases, and at its contacts 21 opens the operating circuit to the vertical magnet, at its contacts 82 closes a further point in the circuit to release magnet 100, and at its contacts 83 closes a self-interrupting operating circuit to rotary magnet 110 over contacts 67, 12, 28, 111, 77 and 83. If all trunk lines on the selected level are busy, the switch wipers 134, 135 and 136 will be stepped in a well-known manner to the eleventh position while the vertical wiper 150 remains engaged with the level contact on the auxiliary bank, whereupon the cam springs 138 are operated to open the operating circuit to relay 60. Relay 60 releases and at its contacts 61 applies busy tone to the line 131 over contacts 71, 61 and 21, at its contacts 62 further opens the dial tone circuit to line 131, at its contacts 63 opens the third winding circuit of line relay 30, at its contacts 64 further opens the operating circuit to the vertical magnet, at its contacts 65 prepares an operating circuit over the wiper 150 to the level or group meter, depending upon the existing meter connections to the contact with which the vertical wiper 150 is engaged. The calling party on receipt of the busy tone restores his handset which opens the operating circuit to relays 30 and 50. Relays 30 and 50 release and at their respective contacts 31 and 51 open the operating circuit to relay 40. Relay 40 holds for a short period. Assuming the vertical wiper 150 is engaged with the eighth contact, a temporary circuit is completed over contacts 27, 32, 43, 65, wiper 150, the eighth contact of the auxiliary bank, through jack box 152 to the level meter 157. After a short period relay 40 releases and opens the aforescribed circuit to the level meter. With this arrangement a plurality of selectors of a group will be connected as illustrated by incoming leads 153 and each selector will ordinarily register all trunks busy when they rotate to the overflow position. The jacks in the jack box 152 are connected to the contacts on auxiliary bank 151 by a group of conductors, each conductor being individual to a contact and a jack. Various circuit arrangements can be devised by employing a various number of meters and jumpers. In the arrangement shown a level meter is connected to the jack for the eighth level of the selector and jumpers are inserted into the remaining jacks to multiple the remaining levels to a group meter. The all trunk busy periods of the eighth level will thereby be monitored individually, but the levels of contacts corresponding to the multiplied contacts will be monitored as a group without indicating which level has all trunks busy. Many other arrangements are immediately apparent and further de-

tail is unnecessary. Relay 40 on releasing at its contacts 44 completes a circuit to release magnet 100 over contacts 27, 32, 44, 82 and 76. Magnet 100 operates and releases the switch thereby opening the operating circuit to relay 70. Relay 70 restores and the switch is ready for a subsequent call.

If the selected level is not busy the switch will stop rotating when the wiper 136 finds an idle trunk with battery potential thereon. A circuit will then be completed for relay 10 over contacts 66. Relay 10 operates and at its contacts 11 completes an operating circuit for relay 20 over contacts 67 and at its contacts 12 opens the operating circuit to rotary magnet 110. The rotary motion is thereby stopped. Relay 20 operates and at its contacts 21 and 23 opens the operating circuit to line relays 30 and 50, at its contacts 22 and 24 connects lines 131 and 132 to 134 and 135, at its contacts 25 connects line 133 to line 136 and thereby extends the C lead through the selector, at its contacts 29 closes a temporary holding circuit for itself over contacts 41 and 26, at its contact 27 opens a further point on the release magnet circuit and at its contact 28 opens a further point in the rotary magnet circuit.

Relays 30 and 50 restore and at their respective contacts 31 and 51 open the circuit to relay 40. Relay 40 at its contacts 43 opens the holding circuit to relay 60. Relay 60 releases and opens the operating circuits to relays 10 and 20 at its contacts 66 and 67. Relays 20 and 70 remain operated during the completed connection, relay 20 being maintained in the energized condition by a ground returned over wiper 136 from a succeeding switch.

Release of the switch is effected in a normal manner. When the calling party hangs up ground is removed from conductor 136 and relay 20 releases. Relay 20 at its contacts 27 completes an operating circuit to release magnet 100 over contacts 27, 32, 44, 82 and 76. Release magnet 100 operates and effects release of the selector switch in a well-known manner. Off normal springs 137 thereupon open the circuit to off normal relay 70 which releases and at its contacts 76 opens the operating circuit to release magnet 100. The release magnet restores and the selector is restored to normal.

While a particular embodiment of the invention has been described, it will be understood that various modifications may be made therein which are within the true spirit and scope of the invention.

What is claimed is:

1. In a two-motion automatic switch, a vertical bank having a plurality of contacts and a rotary bank having a plurality of contacts arranged in a plurality of levels, each contact of said vertical bank being associated with a different one of said rotary bank contact levels, a meter connected to one of said contacts on said vertical bank, means for busying certain of said rotary bank contacts, a vertical wiper on said switch having access to said vertical bank contacts, other wipers on said switch having access to said rotary bank contact levels, means for operating said switch in a vertical motion to simultaneously move said vertical wiper into engagement with said meter contact and position said other wipers opposite the rotary bank level associated with said meter contact, means for operating said switch in a rotary motion to move only said other wipers across said contacts of said rotary bank level.

associated with said meter contact while maintaining said vertical wiper in engagement with said meter contact, a circuit including said meter contact and said vertical wiper for operating said meter, and means for completing said circuit to operate said meter in case all said contacts of said rotary bank level associated with said meter contact were busy during said rotary motion of said switch.

2. In a two-motion automatic switch, a vertical bank having a plurality of contacts and a rotary bank having a plurality of contacts arranged in a plurality of levels, each contact of said vertical bank being associated with a different one of said rotary bank contact levels, a meter connected to one of said contacts on said vertical bank, means for busying certain of said rotary bank contacts, a vertical wiper on said switch having access to said vertical bank contacts, other wipers on said switch having access to said rotary bank contact levels, means for operating said switch in a vertical motion to simultaneously move said vertical wiper into engagement with said meter contact and position said other wipers opposite the rotary bank level associated with said meter contact, means for operating said switch in a rotary motion to move only said other wipers across said contacts of said rotary bank level associated with said meter contact while maintaining said vertical wiper in engagement with said meter contact, a cam relay included in said switch, circuit means for operating said cam relay, cam springs included in said cam relay circuit operated in case all said contacts of said rotary bank level associated with said meter contact were busy during said rotary motion to open said cam relay operating circuit for releasing said operated cam relay, a circuit including said meter contact and said vertical wiper for operating said meter, and contacts controlled responsive to said release of said cam relay for completing said meter circuit to operate said meter.

3. In a two-motion automatic switch, a vertical bank having a plurality of contacts and a rotary bank having a plurality of contacts arranged in a plurality of levels, each contact of said vertical bank being associated with a different one of said rotary bank contact levels, a meter connected to one of said contacts on said vertical bank, means for busying certain of said rotary bank contacts, a vertical wiper on said switch having access to said vertical bank contacts, other wipers on said switch having access to said rotary bank contact levels, means for operating said switch in a vertical motion to simultaneously move said vertical wipers into engagement with said meter contact and position said other wipers opposite the rotary bank level associated with said meter contact, means for operating said switch in a rotary motion to move only said other wipers across said contacts of said rotary bank level associated with said meter contacts while maintaining said vertical wiper in engagement with said meter contact, a line relay and a slow-to-release relay associated with said switch, circuit means for operating and releasing said line relay, other circuit means controlled by said operation of said line relay for operating said slow-to-release relay, additional circuit means including said vertical wiper and said en-

gaged meter contact for operating said meter, means for preparing said meter circuit in case all said contacts of said rotary bank level associated with said meter contact were busy during said rotary motion of said switch, and contacts controlled responsive to said release of said line relay subsequent to all said contacts of said rotary bank level being busy for opening said circuit to said slow-to-release relay and for completing said prepared meter circuit to operate said meter, said metering circuit maintained completed by said slow-to-release relay for a period of time equal to the release time of said slow-to-release relay.

4. In a two-motion automatic switch, a vertical bank having a plurality of contacts and a rotary bank having a plurality of contacts arranged in a plurality of levels, each contact of said vertical bank being associated with a different one of said rotary bank contact levels, a pair of meters associated with said switch, one of said meters being connected to a certain one of said vertical bank contacts and the other of said meters being connected to the remainder of said vertical bank contacts in multiple, means for busying certain of said rotary bank contacts, a vertical wiper on said switch having access to said vertical bank contacts, other wipers on said switch having access to said rotary bank contact levels, means for operating said switch in a vertical motion to simultaneously move said vertical wiper into engagement with one of said vertical bank contacts and position said other wipers opposite the rotary bank level associated with said one vertical bank contact, means for operating said switch in a rotary motion to move only said other wipers across said contacts of said rotary bank level associated with said one vertical bank contact while maintaining said vertical wiper in engagement with said one contact, a circuit at times including said vertical wiper and said certain vertical bank contact for operating said one meter and at other times including said vertical wiper and any one of said multiplied remainder of vertical bank contacts for operating said other meter, and means for at times completing said circuit to operate said one meter in case all said contacts of said rotary bank level associated with said certain vertical contact were busy during said rotary movement of said switch and for at other times completing said circuit to operate said other meter in case all said contacts of any one of the remainder levels associated with said remaining multiplied vertical contacts were busy during said rotary movement of said switch.
